DESIGN FOR A PLASTIC SHEET OR SIMILAR ARTICLE

Harry E. Smith, Short Hills, N. J., assignor to Celluloid Corporation, a corporation of New Jersey

Application February 7, 1936, Serial No. 61,024

Term of patent 7 years

To all whom it may concern:

Be it known that I, Harry E. Smith, a citizen of the United States, residing at Short Hills, county of Essex, State of New Jersey, have invented a new, original, and ornamental Design for a Plastic Sheet or Similar Article, of which the following is a specification, reference being had to the accompanying drawing, forming part thereof.

In the accompanying drawing:

The figure is a plan view of a plastic sheet or similar article showing my new design.

The thickness of the sheet or similar article is not an important part of the design. The

dominant feature of the ornamentation of the sheet or similar article shown on the drawing is the arrangement of alternating strips, each strip being composed of alternating strata of contrasting colors. The strata in adjacent strips are arranged at sharply different angles.

I claim:

The ornamental design for a plastic sheet or similar article, substantially as shown and described.

In testimony whereof, I have hereunto subscribed my name.

HARRY E. SMITH.
